UNITED STATES PATENT OFFICE.

HARRY L. ALKUS, CHARLES A. SINCLAIR, AND WILFRED T. KRIGBAUM,
OF OAKLAND, CALIFORNIA.

COLLAR.

SPECIFICATION forming part of Letters Patent No. 770,250, dated September 20, 1904.

Application filed November 10, 1903. Serial No. 180,499. (No model.)

To all whom it may concern:

Be it known that we, HARRY L. ALKUS, CHARLES A. SINCLAIR, and WILFRED T. KRIGBAUM, citizens of the United States, residing at Oakland, Alameda county, State of California, have invented certain new and useful Improvements in Collars; and we do hereby declare the following to be a full, clear, and exact description of the same.

10 The present invention relates to that class of collars known as detachable turn-down collars, rolled collars, lock-collars, or such as comprise an inner and outer fold, the outer fold being turned over to wholly or partially cover the inner fold.

As at present manufactured the inner fold of the ordinary collar buttons at the front and back to the neckband of the shirt. The result is that it is exceedingly difficult to put on 20 the tie after the collar is attached to the shirt, due to the fact that the outer fold of the collar is so drawn to the inner fold as to render it almost impossible to place the tie properly after the collar is secured to the shirt. This 25 requires that the tie be placed within the folds of the collar prior to securing the same to the shirt. Even then it is difficult to form the tie, as the friction between the same and the walls of the collar precludes free movement of the 30 tie or scarf for adjustment. The result is that the strain required to move the tie or scarf acts upon the front buttonholes of the collar and breaks the same, so that in a short time the collar by reason of the torn or enlarged 35 buttonholes becomes practically useless.

The objects sought to be attained by the present invention are, first, the construction of a collar which will permit of the tie being easily and quickly secured after the collar has 40 been attached to the neckband of the shirt; second, the construction of a turn-down collar which allows free adjustment of the tie; third, the construction of a collar wherein the outer fold thereof is secured to the back of the shirt 45 instead of the inner fold, and, fourth, the formation of a turn-down collar with less material than usually employed in the manufacture of similar style of collars.

To comprehend the invention, reference should be had to the accompanying sheet of 50 drawings, wherein—

Figure 1 is a front perspective view of the improved collar. Fig. 2 is a similar view of the collar viewed from its rear. Fig. 3 is an inner plan view of the collar, and Fig. 4 is a 55 broken detail view disclosing a portion of the collar, said view mainly illustrating the running of the necktie at the back of the collar.

The collar comprises an outer fold 1 and an inner fold 2. Ordinarily the back buttonhole 60 is in the inner fold 2 of the collar, the same being substantially covered or hidden from view by the outer fold 1. In our improved collar the inner fold is cut away from point 4 to 5, so that the lower edge of said fold is 65 brought a distance above the lower edge of the outer fold. The forward or overlapping or lap surfaces 6 7 of the inner or under fold 2 remains as usual in this class of collars, so that the collar when in position presents the 70 appearance designed to be obtained by such collars. In these portions of the inner or under fold of the collar the buttonholes 8 are formed. The lower edge of the outer fold 1 at the rear portion of the collar is preferably 75 cut away at 9 9', so as to provide a depending tongue 10. In this tongue is formed a button-hole 11, which receives the rear collar-button 12 of the shirt. It will thus be observed that instead of uniting the inner or under fold 2 80 of the collar to the shirt at the back thereof the outer fold of the collar at such point is united to the shirt. By so uniting the collar the under fold thereof is held firmly down to the shirt-band instead of being forced therefrom by the head of the rear shirt-button. 85

With the described formed collar the tie may be readily inserted after the collar has been buttoned to the shirt-band. When so buttoned, the appearance of the collar will be 90 that illustrated by Fig. 1 of the drawings. To adjust the tie 13, it is only required to pass the same between the outer fold of the collar and the neckband of the shirt, the rear portion of the tie resting upon or covering the tongue 95 10, Fig. 4 of the drawings. As said tongue is

buttoned to the neckband of the shirt, the tie is held from displacement by moving upward. In fact, it is held down in the same manner as though passed through a loop attached to the 5 back of the shirt. This is due to the fact that the tie is placed over the tongue 10 and then slipped beneath the outer fold 1 at the cut-away portions 9 9'. The tie is thus held positioned in the back against upward movement 10 by reason of the outer fold at such point being secured directly to the shirt, it being held between the overlapping surface 6 7 of the inner fold 2 and the inner surface of the outer fold 1 at the front of the collar. 15 By the use of the described collar any style of neck wear or tie may be quickly adjusted to the collar and be secured in place after the collar has been attached at front and back to the neckband of the shirt. The life of the 20 collar is materially prolonged, inasmuch as the tie slips freely beneath the outer fold of the collar. Hence the buttonholes are not injured by the strain exerted thereon to overcome the resistance ordinarily offered to the 25 free movement of the tie. Again, the cost of the collar to the manufacturer is materially reduced, due to the saving in material effected by the removal of the section designated from the inner fold of the collar. 30 Having thus described the invention, what

is claimed as new, and desired to be protected by Letters Patent, is—

1. As a new article of manufacture a detachable turned-down collar, the outer fold of which is formed with a rear buttonhole so as 35 to enable said fold to be secured to the rear button of a shirt, a portion of the surface of said outer fold being cut away at each side of the rear buttonhole, adapted for the insertion of a portion of the tie therethrough. 40

2. As a new article of manufacture a detachable turned-down collar, the outer fold of which is formed with a rear buttonhole, the lap-surfaces of the inner fold being formed with buttonholes for securing the collar at its 45 front, the body of the inner fold being partially removed intermediate the lap-surfaces, and the outer fold having a rear buttonhole, and cut-away portions at its lower edge at the respective sides of said buttonhole adapted 50 for the insertion of a portion of a tie therethrough.

In witness whereof we have hereunto set our hands.

HARRY L. ALKUS.
CHARLES A. SINCLAIR.
WILFRED T. KRIGBAUM.
